DESIGN FOR A DOLL CARRIAGE

James G. Balmer, Jr., Detroit, Mich., assignor to
United States Rubber Company, New York,
N. Y., a corporation of New Jersey

Application August 16, 1947, Serial No. 140,921

Term of patent 7 years

(Cl. D34—15)

To all whom it may concern:

Be it known that I, James G. Balmer, Jr., a citizen of the United States of America, residing in Detroit, county of Wayne, and State of Michigan, have invented a new, original, and ornamental Design for a Doll Carriage, of which the following is a specification, reference being had to the accompanying drawings, forming part thereof, wherein:

Fig. 1 is a top plan view of a doll carriage, showing my new design, the top thereof being in the lowered position;

Fig. 2 is a side elevational view of the carriage shown in Fig. 1;

Fig. 3 is a longitudinal vertical sectional view thereof taken along line 3—3 in Fig. 1;

Fig. 4 is a transverse vertical sectional view thereof taken along line 4—4 in Fig. 1; and

Fig. 5 is an end elevational view of the handle end of the carriage, the top being in the raised position.

I claim:

The ornamental design for a doll carriage, as shown.

JAMES G. BALMER, JR.
